(57) **CLAIM**

The ornamental design for a shrimp ring having tray with transparent cover, as shown and described.

DESCRIPTION

FIG. 1 provides a perspective view of a shrimp ring showing my new design;

FIG. 2 is a top plan view of the shrimp ring of FIG. 1;
FIG. 3 is a side elevation view of the shrimp ring of FIG. 1,
that, due to symmetry of the shrimp ring, is the same from
any side; and,

FIG. 4 is a bottom plan view of the shrimp ring of FIG. 1.
